UNITED STATES PATENT OFFICE

ARTHUR VON OSTERMANN, OF NEW YORK, N. Y., ASSIGNOR TO SEEOSTRA IMPORT CORPORATION, OF NEW YORK, N. Y., A CORPORATION OF NEW YORK

DESIGN FOR A LINGERIE RIBBON

Application filed October 28, 1930. Serial No. 37,421. Term of patent 3½ years.

To all whom it may concern:

Be it known that I, ARTHUR VON OSTERMANN, a citizen of the United States, residing at New York, in the county and State of New York, have invented a new, original, and ornamental Design for a Lingerie Ribbon, of which the following is a specification, reference being had to the accompanying drawing, forming part hereof.

The drawing is a plan view showing the lingerie ribbon.

I claim:

The ornamental design for a lingerie ribbon, as shown.

ARTHUR VON OSTERMANN.
